STITCHING

William Schwartz, New York, N. Y., assignor to
 La Marquise Footwear, Inc., New York, N. Y.,
 a corporation of New York

Application June 7, 1944, Serial No. 539,055

7 Claims. (Cl. 36—19.5)

1

The present invention has an important application in the art of boudoir slippers, but is applicable also to other types of footwear, and in certain of its broader aspects, the invention is applicable to a wide variety of stitched structures and to methods of producing the same.

An object of the invention is to provide an article of footwear affording a seam between the rim of the upper and the portion of the sole body thereto attached, which seam shall have the ornamental appearance of an expensive hand-made cross-stitch, and though of inelastic thread or strand shall add to the comfort of wear by yielding slightly to the movement of the foot.

Another object is to provide an article of footwear having a seam of the above type which may be produced by the use of an ordinary high-speed zigzag lock stitch sewing machine.

Another object is to provide a stitch and a method of making the same which serves for securely binding the exposed finished edge of one strong piece of fabric to an adjoining like fabric in substantially edge to edge abutting relationship, which effectively distributes tensile strain tending to draw such abutting fabrics apart, and has the ornamental appearance of an expensive hand-made cross-stitch, but may be produced rapidly and at low cost by resort to a conventional type of sewing machine.

Another object is to provide a stitch and a method of making the same which shall be secure and ornamental in appearance and capable of being mechanically made in a wide variety of applications other than those above referred to.

In the accompanying drawings in which are shown one or more of various possible embodiments of the several features of the invention,

Fig. 1 is a perspective view of a slipper embodying the invention and showing part of the under-sole partially withdrawn to reveal the general construction,

Fig. 2 is a perspective view on a greatly enlarged scale showing the outer or exposed side of the seam as applied to an article of footwear,

Fig. 3 is a view similar to Fig. 2 showing the inner or concealed side of the seam,

Fig. 4 is a perspective view showing the inter-relation between the threads or strands that make up the seam,

Fig. 5 is a perspective view illustrating the method of producing the seam with the use of a conventional type of sewing machine,

Fig. 6 is a transverse sectional view taken on line 6—6 of Fig. 5,

2

Fig. 7 is a perspective view showing the seam spreading operation,

Fig. 8 is a fragmentary perspective view showing a piping arrangement incorporating features of the present invention, and

Fig. 9 is a view similar to Fig. 8 showing a decorative seam incorporating the broader principles of the present invention as applied to a simple piece of fabric.

Referring now to the drawings the invention is shown incorporated in a boudoir slipper of the general type disclosed in the prior patent to Sal Pepitone No. 2,344,057 issued March 14, 1944. The upper has an insole 10 provided with a rim or border 11 to which is attached by a line of stitching S a binder strip 13 drawn inward snugly at 14 to encompass the edge of a sole body 15 the lower or raw face of which has adhesively attached thereunder the bottom sole 16. The details of construction of this slipper are by themselves not material to the present invention and therefore need not be described more fully. The present invention resides in the particular stitching and the method of forming the same by which the insole is attached to the binder.

The binder strip may consist of a narrow piece of fabric 13, desirably matching that of the upper, backed by a corresponding strip 17 of strong duck adhesively bonded thereto. The upper edge of the binder strip is desirably turned inwardly as at 18 and adhesively held to the body thereof. As shown in the drawings, the trimming border 11 of the insole 10 which, prior to assembly in the shoe, would extend in a horizontal plane, is made to extend downward at substantially right angles to the insole and its free edge 19 is abutted by the inturned edge of the binder strip.

The seam, as shown, has the appearance of an ornamental cross-stitch and the intersections preferably extend along said edge 19.

Preferably, the ornamental stitch is made up of a pair of threads or strands 20 and 21, each of zigzag form, which are interlooped at alternative vertices thereof as at 22 along the edge 19, at which region the interlooped threads are superposed over, but do not penetrate the fabrics. The strand or thread 20 penetrates the border 11 at its line of intervening vertices 23 and the other strand or thread 21 is substantially embedded in the binder strip 13 at its line of intervening vertices 24. Said vertices 23 and 24 are aligned transversely of or along a line normal to the abutting edges 19. Preferably, the strand 20 penetrating the fabric at each vertex 23 extends as

concealed reversely doubled lengths, or in other words as two parallel connected bridge lengths 25 and 26 on the rear side of the connected fabric pieces across the abutting edges 19 for interlooping as at 27 with the vertex joining the two short companion lengths 28 and 29 of the corresponding directly opposed vertex of the other strand or thread 21. Said interloop 27 is preferably substantially embedded within the thickness of fabric 13 and its backing 17, as is evident from the absence of the interloop 27 from Figs. 2 and 3.

The interlooped vertices 22 exposed along the abutting edges 19 do not penetrate the fabrics, or either of them, but lie snugly thereagainst to keep the fabric edges in abutment in a common plane without the danger, incurred if the stitch penetrated the fabric substantially at its free edge, of breaking through under the strain of wear.

The two strands or threads making up the stitch extend about the entire periphery of insole and binder and afford a particularly secure seam therebetween. This seam will not only take the strain exerted thereon in snugly drawing the binder strip 13 about the sole body as shown in Fig. 1, but in the actual use of the slipper or other article of footwear, the seam, constructed as described, will accommodate the strain incurred in walking or in exercising of the toes or foot within the slipper. Were the binder strip connected to the upper by the ordinary straight lock stitch, strain would tend to loosen or break the longitudinal runs of thread. In the case of the present seam, however, each approximately open square s of which the design of stitch is made up would be distorted slightly into a diamond or oblong at the region of increased strain. The strain applied in use at any one needle hole is distributed along four thread runs, two of which extend obliquely to distribute the strain over the interlooped companion thread or strand and the other two of which extend directly across the abutting fabric edges to divide the strain with the companion needle hole. The strands are free to slide at each needle hole as well as at the interlooped portions 22 and 21 to furnish the added length for the distortion above set forth in rendering each strained square element s somewhat rhombus or diamond-shaped. Upon relief of the strain described the parts return to their original position by reason of the slight resilience of the materials if not of the thread or strand.

The stitch, aside from its ornamental appearance, mechanical security and adaptability to strain, as noted, has the further advantage of simulating the appearance of an expensive hand-made cross-stitch.

The stitch as described is claimed as such, and also in its particular utility for footwear purposes, regardless by what methods or mechanism it is made. However, a preferred and economical method also claimed herein of producing the stitch will now be set forth.

For this purpose, as shown in Figs. 5 and 6, the border 11 of the insole 10 is superposed, desirably in exact registering relation over the finished inturned edge 18 of the binder strip 13. For making the cross-stitch, the thread or strand 20 is applied from the top while the companion thread or strand 21 is applied from the bottom, that is, from the underside of the binder strip, the interlooping of the two strands occurring alternately at the vertices 24 at the underface of the superposed fabrics and at the edge 19 immediately beyond the two superposed fabrics.

The mode of stitching thus described is most

effectively accomplished by the use of a conventional high-speed zigzag lock stitch sewing machine of any of various designs now on the market. The machine is so adjusted that the thrusts 5 of the needle alternate through the superposed insole border and binder and at the registering superposed edges of the said two pieces. For this purpose a suitable foot 33 slotted at 34 to accommodate the transverse needle movement of said zigzag machine, cooperates with a gauge 35 adjustable at 36 for positioning the superposed edges of the fabric pieces fed through the machine. Accordingly, the strands become interlooped at 22 against the edges of the two pieces without penetrating the latter. Desirably, the conventional thread controller, take-up or tension (not shown) of the sewing machine is loosened for both the needle and the bobbin feeds to attain considerable slack of both threads.

After the stitching operation set forth has been completed the superposed edges of border and binder are spread outwardly. This is best done as shown in Fig. 7 by passing the stitched fabric through a roll press with milled rollers 31 and 32. The thickened interloop 27, shown exposed at the left of Fig. 7, is drawn into the thickness of the backed binder strip 13 in this rolling operation and becomes anchored there, and the slack in the threads or strands permits the superposed borders of the two fabrics to be spread apart into substantially a common plane to bring the extreme edges of the fabrics into substantially abutting relationship with the interloop vertices 22 substantially aligned along the abutting edges of border and binder as shown at the right of Fig. 7. If desired, the roll press could be incorporated in a single unit with the sewing machine to spread out the fabric edges immediately after they have been stitched in the superposed relation set forth. 40 By the spreading operation set forth and shown in Fig. 7 the border 11 of the insole is forced into the plane of the adjacent portion of the binder to constitute a continuation thereof. Each superposed pair of needle holes in Figs. 5 and 6 45 penetrating insole and binder strip respectively being thus drawn apart to assume a position at opposite vertices 23, 24 of the spread out attached fabrics form an open square stitch element s of the cross-stitch thus produced.

Thus, the stitch described above, with all the advantages resulting from its use, may be produced mechanically in the simple manner last described uniformly and with considerable expedition. When the upper with the binder strip 55 thus peripherally attached to the insole is now assembled with the sole body, the border 11 of the insole extends at substantially right angles to the area of the insole peripherally about the upper part of the sole body and in the plane of the abutting upper edge 19 of the binder strip.

While the invention has been described in a preferred application for which it has been particularly designed, it will be understood that the stitch set forth has utility in other arts, more especially where it is utilized to connect a relatively thick binder, flounce or skirt about the edge or periphery of a relatively thick fabric plaque, plate, disk or panel. Among various applications to which the stitch and method of producing the same would lend itself particularly are to bed-spreads, table covers, hat bodies, lampshades, furniture, typewriter and fan covers, duffle-bags and countless other articles in which a face or top piece or crown has attached there- 70 about a peripheral side piece or skirt.

The seam of the invention in still broader applications is useful for attaching together two relatively stiff or thick pieces of fabric that lie substantially in a common plane as, for instance, in the manufacture of drapes, or for the attachment of a selyage, flounce, border or piping to any relatively thick or stiff piece of fabric. In Fig. 8 is illustratively shown a cord 37 enclosed by the edge 38 of the fabric 39, and attached thereto by the zigzag stitch made up of strands 40 and 41 interlooped at 42 along the rounded edge of the structure, and penetrating the two plies of the fabric beyond the cord at 43. The thread take-up would be tightened rather than loosened in making up this structure, by use of a zigzag lock stitch machine.

The invention is also applicable for conveniently applying upon a single relatively thick piece of fabric an ornamental design of stitching. One such application is shown in Fig. 9, in which the single piece of fabric is bent along line 45 to form superposed layers 46 and 47, shown in dotted lines, which are stitched in the manner shown in Fig. 5 and then spread in the manner shown in Fig. 7 as above described. The thick fabric forms a sort of bead 48 held against spread by the bridge lengths (not shown, but corresponding to elements 25, 26 in Figs. 3 and 4), the exposed interlooped vertices 49 of the two strands or threads 50 and 51 extending over the median line of bead 48 as shown.

As many changes could be made in the above construction, and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. In an article of footwear of the type comprising a pair of fabrics consisting of an insole having a downturned trimmed border and a binder strip having an inturned border in substantially edge to edge engagement with said downturned border, and a sole body encompassed by said binder and said downturned border and cross-stitching attaching said binder to said border, the combination in which said stitching comprises a pair of strands each extending in a zigzag path with alternate vertices of the strands interlooped, said interlooped vertices extending substantially along the line of contact of border and binder and being superposed thereover at the outer face of the article, the intervening vertices of the respective zigzag strands being opposed to each other, said vertices of one of said strands penetrating one of said fabrics and extending in concealed reversely double lengths transversely across the junction between insole and binder and being interlooped at the center of such double lengths with the intervening vertices of the other strand, said latter vertices being substantially embedded in the other fabric.

2. In an article of footwear of the type comprising a pair of fabrics consisting of an insole having a border and a binder strip attached to said border and exposing the edge of the latter, said border being downturned substantially in the plane of the binder and a sole body encompassed by said body and border and cross-stitching connecting said border and binder; the combination in which said cross-stitching comprising

a pair of strands each extending in a zigzag course, one exposed on the border and the other on the binder, said strands being interlooped at alternate vertices thereof substantially along the exposed edge of the border at the outer face of the article, one of the strands at each intermediate vertex thereof penetrating one of the fabrics and having a pair of concealed reversely doubled lengths transversely of the border edge and interlooped with the corresponding concealed opposed vertex of the other strand, said latter vertex being substantially embedded in the other fabric.

3. In an article of footwear of the type comprising an insole having a finished border strip about the periphery thereof, and a binder strip of lined fabric having an inturned edge substantially in edge to edge abutting relationship with respect to the edge of said border, the upper part of said binder and the adjacent part of the said border encompassing the edge of a sole body, and cross-stitching connecting said border and said binder; the combination in which said stitching comprises a pair of interlinked strands, each extending in a zigzag path with alternate vertices of the strands interlooped along the abutting edges of the border and binder and superposed thereover at the outer face of the article, and intervening vertices of the respective strands aligned transversely of each edge, said intervening vertex of one strand penetrating the insole border and extending as a concealed reversely doubled length, the center of such doubled length being interlooped with the corresponding vertex of the other strand, said latter interlooped vertex being substantially embedded within the thickness of the binder strip.

4. The method of attaching to the border of a first element, a strip, which consists in superposing the edges of the said elements and forming a connecting seam therebetween by interlinking a pair of strands in alternate operations respectively immediately beyond the superposed edges and through the superposed materials and thereupon applying tension transversely to said elements to spread the stitch connecting the first element and the strip, thereby to dispose the faces of the former substantially into the same plane with those of the latter.

5. The method of attaching a first fabric element to a second fabric element, which consists in passing said elements with their borders in superposed relation through a zigzag sewing machine set to pass the needle alternately immediately beyond the edge of the superposed fabrics and through said fabrics, to interloop the two strands at each complete in and out needle stroke, said stitching operation being performed with slack in the strands, and thereupon transversely spreading the stitched superposed fabrics apart into substantially a common plane with take-up of said slack.

6. A seamed article comprising a pair of fabrics, the edge of one of said fabrics being adjacent the other fabric, and an ornamental seam connecting said fabrics near said edge, said seam comprising a pair of strands each extending in a zigzag course, said strands being interlooped at alternate vertices and said vertices being along said edge, the intervening vertices of one strand penetrating one of the fabrics, the intervening vertices of the other strand being substantially embedded in the other fabric, said intervening vertices of the two strands being in alignment transversely of said edge, the strand through one of said fabrics extending in reversely doubled trans-

verse lengths from each penetrating vertex along the rear faces of the fabrics and being interlooped with the opposed substantially embedded looped vertex of the other strand.

7. A seamed article comprising a pair of fabrics in edge to edge abutting relationship and an ornamental seam connecting said fabrics at said edge, said seam comprising a pair of strands each extending in a zigzag course, said strands being interlooped at alternate vertices and said vertices being along the exterior of said abutting edges, the intervening vertices of one strand penetrating one of the fabrics, the intervening vertices of the other strand being substantially embedded in the other fabric, said intervening vertices of the two strands being in alignment transversely of said abutting edge, the strand through one of said fabrics extending in reversely doubled transverse lengths from each penetrating vertex along the rear faces of the fab- 20

rics and being interlooped with the opposed substantially embedded looped vertex of the other strand.
